UNITED STATES PATENT OFFICE

HENRY K. WACK, OF NEW BEDFORD, MASSACHUSETTS, ASSIGNOR TO JOHN I. PAULDING, INC., OF NEW BEDFORD, MASSACHUSETTS, A CORPORATION OF MASSACHUSETTS

ELECTRIC LIGHT FIXTURE

Application filed May 16, 1929. Serial No. 363,417.

This invention relates to electric light fixtures and more particularly to a wall bracket for electric lamps.

One of the objects of the invention is the provision of an electric light wall bracket which is of simple construction and which may be assembled rapidly without requiring any fastening means.

Another object of the invention is the provision of a two part bracket in which one of the parts is recessed to hold a lamp socket with its shell portion projecting therefrom and the other part is adapted to be threaded on said shell portion to lock said socket in lamp receiving position and to impart a finished appearance to the bracket.

A further object of the invention is the provision of a bracket of the character described which may be molded from porcelain or other suitable insulating material.

Other objects of the invention will be described hereinafter.

In the accompanying drawings showing one form of the invention, Figure 1 is a front elevation of one form of wall bracket constructed in accordance with my invention; Fig. 2 is a side elevation of the same with an electric lamp mounted therein; Fig. 3 is a rear elevation of the same looking from right to left in Fig. 2; Fig. 4 is a top plan view of the same looking downwardly in Fig. 1; Fig. 5 is a central vertical sectional view of the same showing in side elevation an electric lamp mounted therein; Fig. 6 is a sectional view on line 6—6 in Fig. 5 looking from right to left; Fig. 7 is a sectional view on line 7—7 in Fig. 5 looking downwardly and Fig. 8 is a sectional view on line 8—8 in Fig. 5 looking downwardly.

Referring to the drawings, there is shown a fixture adapted for use as wall bracket comprising two parts, one a wall member 10 serving as a housing for an electric lamp socket and the other an annular member 12 for locking the socket within the wall member in lamp receiving position, both said members being molded from porcelain or other suitable moldable insulating material. The wall member may be of any suitable form but as shown is of oval shape having a centrally

located outwardly extending arm 16. Extending from the rear or inner face of the wall member and into the arm is a straight bore or recess 18 having a semi-circular inner end so positioned that it breaks out through the top side of said arm. Within the recess is mounted an electric lamp socket having a shell portion 20 of usual form for receiving and holding an electric lamp 22 which shell portion registers with the opening in the top of the arm. The annular member 12 may also be of any suitable form but as shown is bell-shaped having an interior thread 24 so that it may be threaded on the outside of the threaded shell 20 to lock the lamp socket in lamp receiving position and to close and conceal the circular opening in the arm and to give the fixture a finished appearance. The opening in the arm and the annular member 12 have complementary shoulder engaging portions 26 and 28 so that the end of the said member 12 fits within the opening in the arm and makes a tight joint when the two parts are assembled.

The bore or recess should be of a form in cross-section corresponding to the cross-section of the lamp socket which is to be mounted in the recess. In the embodiment shown the lamp socket is preferably inserted into the recess sidewise and consequently the recess 18 corresponds in cross-section to a longitudinal section of the socket.

In the drawings the wall member is shown having a recess suitably formed for receiving sidewise a lamp socket of the form shown and described in United States Letters Patent No. 1,700,791 issued to Morey & Brogden November 7, 1911. The socket shown in that patent may be briefly described as comprising two spaced insulating blocks 30 and 31 connected by standards 32, 33 and 34, the first two of which are provided with the usual binding screws 35 and 36 (Figs. 3 and 5). The block 31 has formed on its inner surface four inclines 37 constituting teeth which are segmental in form and the alternate inclines are provided with metallic facings secured thereto, one of which is connected to the standard 33 and the other with the lamp contact 38. A metallic contact plate 39 provided

with two radial arms is rotatably mounted upon a pivot pin centrally mounted in the insulating blocks 30 and 31. Pivotally mounted upon said pin is a segmental operating member 42 preferably of insulating material provided with ratchet teeth on one side adapted to engage said contact plate and a torsion spring 43 coiled on the said pin is so connected to said segmental member that when said member is moved through an arc of a circle by a pull chain 45, the ratchet teeth catch and move the contact plate 39 to engage the next inclines thereby either making or breaking the lamp circuit. When the pull chain is released, the spring turns for new engagement with the contact plate. A flaring guide 46 is fixed to the standard 34 through which the pull chain is operated. The shell 20 is fastened by screws 47 to the outer surface of the insulating block 30, said shell being threaded both on its inside and outside surfaces. For a more complete description, however, of said lamp socket said Letters Patent hereinbefore mentioned may be referred to, since the particular construction of the lamp socket constitutes no part of this invention.

The lamp socket is inserted sidewise into the recess 18 consequently the recess preferably conforms in shape to a longitudinal section of the said lamp socket. The main portion of the recess designated 18 is rectangular in cross section to accommodate the two insulating blocks and intermediate switch mechanism of the socket and the other portion 50 of the recess is reduced in width to accommodate the shell portion of the socket. On one side of the main portion 18 of the recess and opening into it is a passage 52 which opens out on one side of the arm 16, through which passage the pull chain 45 and flaring guide 46 are moved in inserting the lamp socket into the arm 16 (Fig. 3), the guide being exposed to view on one side of the arm with the pull chain in operative position when the lamp socket is in final position (Fig. 1). The portion 54 of the recess is formed during the molding process in shaping the shouldered portion 28 of the opening in the arm for receiving the annular member 12 (Fig. 6).

The assembling of the fixture for installation is a matter of extreme simplicity and involves nothing more than presenting the lamp socket sidewise to the opening of the recess in the rear face of the wall member, first, dropping the pull chain down into the passage 52 and then dropping the socket member into the recess with the flaring guide in said passage following the pull chain. When the socket member has reached the bottom of the recess, that is, in the end of the arm the annular member 12 is then screwed onto the outside of the shell and tightened up to close the opening in the arm and to lock the socket in position to receive the electric

lamp. Since the shoulder portions 56 in the walls of the recess constitute a restricted portion of the recess the lower part of the lamp socket made up of the two insulating blocks and intermediate switch mechanism is locked within the recess and cannot be withdrawn through the circular opening in the arm which facilitates the setting up of the annular member. It will be apparent that the entire assembling operation may be very rapidly performed with the expenditure of comparatively little time or effort.

Fixtures may be thus assembled for sale and shipment in one piece thereby obviating all danger of losing parts. In installing the fixture, the annular member is unscrewed and the socket dropped out of the wall member, the conductors attached to the binding screws, the socket again mounted in the wall member, the annular member screwed in place and the fixture fastened to the wall or other surface by two screws inserted in the holes 60.

The fixture illustrated in the drawings has been shown with the lamp extending upwardly but the wall member may be mounted in any desired position either to have the lamp depending or extending laterally to one side or the other. Although the invention is shown in connection with a single lamp fixture it is apparent that it is capable of use for fixtures having two or more lamps in different arrangements and for lamp sockets of different constructions by merely varying the number, form or arrangement of the recesses or by providing one recess shaped to take and lock a number of sockets within the wall member. The two parts of the fixture may also be made in a large variety of forms without departing from the invention.

It will be observed that the fact that both parts of my fixture are designed to be molded from porcelain or other suitable moldable insulating material conduces to rapidity and cheapness of production.

It is further to be understood that my invention is not to be limited to the precise form herein shown and described since it is capable of embodiment in a wide variety of forms within the scope of the following claims.

What I claim is:

1. A wall fixture comprising a wall member provided with an interior recess extending from its inner face and opening laterally on one side only of its front face, a lamp socket mounted sidewise within said recess from the back face of said member, said socket comprising a switch portion and a shell portion, and an annular member threaded on said shell portion for locking said socket in lamp receiving position.

2. A wall fixture comprising a wall member provided with a straight interior bore or recess having a single lateral opening in

the front face of said member, a lamp socket comprising switch and shell portions mounted sidewise in said bore or recess with its shell portion projecting through said opening and an annular member threaded on said shell and fitting said opening.

5. A wall fixture comprising a wall member having an arm portion open on one side and an interior recess opening from its rear face and extending to said opening in said arm portion, said recess being of a size and shape in cross-section to accommodate a lamp socket inserted sidewise therein from the inner face of said wall member, a lamp socket mounted in said recess and having a shell portion and an annular lamp member threaded on the exterior of the shell portion of said socket member for closing said opening in the arm portion of said wall member.

10. 4. A wall fixture comprising a wall member having a projecting portion on its front face having a single lateral opening and an interior recess extending from its rear face to the said lateral opening, a lamp socket comprising switch and shell portions mounted in said recess with its shell portion projecting through said lateral opening and an annular lamp member threaded on the shell portion of said lamp socket for closing said lateral opening of said recess and for locking the said lamp socket in lamp receiving position.

25. 5. A wall fixture comprising a wall member provided with a recess extending from its inner face through said member and opening in a single lateral direction in the front face of said member, a lamp socket comprising switch and shell portions mounted in said wall member with its shell portion in said lateral opening and a member threaded on said shell member for closing said lateral opening and locking said socket in lamp receiving position.

30. 6. A wall fixture comprising a wall member having a centrally disposed projecting portion, said wall member having a recess extending from its rear face into said projecting portion and opening through a side portion thereof and being provided with a guideway extending longitudinally said recess and connected thereto by a restricted opening throughout its entire length, said guideway opening out on the other side of said projecting portion, a pull chain lamp socket mounted sidewise in said recess with its pull chain and guide portion in said guideway and a lamp member threaded on the shell portion of said socket for holding it locked in lamp receiving position within said wall member.

35. 7. A two-part wall fixture, one of said parts being adapted to fit against the wall and being provided with an interior recess extending from its rear face and opening laterally in the front face thereof and with a pull chain guideway opening in said front

face, a pull chain lamp socket mounted sidewise in said recess with its shell portion projecting through said lateral opening in the front face of said first part and with its pull chain in said guideway opening and the other of said parts being threaded on the shell portion of said socket for locking it in lamp receiving position.

8. A wall fixture comprising a wall member having an arm formed on its front face and a recess extending from its inner face into said arm, said recess being so positioned as to open out on one side only of said arm, a lamp socket comprising switch and shell portions mounted at the inner end of said recess with its shell portion in register with said side opening in said arm and an annular member threaded on said shell member for locking said socket in lamp receiving position.

9. A wall fixture comprising a wall member having an arm formed on its front face and a straight recess extending from its inner face into said arm, said recess being so positioned as to open out on one side only of said arm and being of a size and shape in cross section permitting a lamp socket to be inserted sidewise therein, a lamp socket mounted at the inner end of said recess with its shell portion in register with said side opening in said arm and an annular member threaded on said shell member for locking said socket in lamp receiving position and for closing said side opening.

10. A wall fixture comprising a wall member having an arm formed on its front face and a recess extending from its inner face into said arm and opening outwardly through the side of said arm, said recess being of a size and shape permitting a lamp socket to be inserted sidewise thereinto from the inner face of said wall member, a lamp socket mounted in the inner end of said recess with its screw portion projecting through the side opening in said arm and an annular member threaded on said shell member for locking said socket in fixed lamp receiving position and for concealing said arm opening.

11. A wall fixture comprising a wall member provided with an interior recess extending from its inner face and opening laterally on one side only of its outer face, a lamp socket, including switch and shell portions, mounted in said recess with its shell portion in said opening and an annular member threaded on said shell portion for locking said socket in lamp receiving position; said interior recess being of a size and configuration in cross-section permitting said lamp socket to be inserted sidewise therein.

12. A wall fixture comprising a hollow wall member having a single lateral opening in its front face, a lamp socket comprising switch and shell portions mounted inside said hollow member with its shell portion in said lateral opening, the interior of said member

being so formed as to require said socket to be inserted sidewise therein from the inner face thereof and to lock said socket against withdrawal through said lateral opening and an 5 annular member threaded on said shell member for locking said socket in lamp receiving position.

In witness whereof, I have hereunto set my hand this fourteenth day of May, 1929.

10. HENRY K. WACK.
